UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

SEMI-AUTOMATIC BLAST-GATE FOR CENTRIFUGAL COMPRESSORS.

1,063,596.

Specification of Letters Patent.

Patented June 3, 1913.

Application filed November 15, 1911. Serial No. 660,400.

To all whom it may concern:

Be it known that I, RICHARD H. RICE, a citizen of the United States, residing at Lynn, county of Essex, State of Massachusetts, have invented certain new and useful Improvements in Semi-Automatic Blast-Gates for Centrifugal Compressors, of which the following is a specification.

My invention relates to a gate or valve for use in the intake pipe of a centrifugal air compressor in connection with a governing mechanism for controlling its driving motor. When such a compressor is employed to supply air to a blast furnace, it is preferably provided with an automatic regulating mechanism which insures the delivery of a predetermined volume of air per unit of time, the pressure varying with the conditions existing in the furnace or other apparatus receiving said air. Thus if the contents of the furnace tend to clog the tuyers thereby obstructing the flow of air, the consequent tendency to reduction in volume of the air acts to increase the speed of the engine or motor driving the compressor so as to increase the air pressure and restore the desired volume.

When the machine is blowing into a capacity, that is into large reservoirs consisting of large pipes, stoves, etc., and operating at such volumes that the discharge vanes under the particular conditions of pressure and volume are not adapted to give the best efficiency, the machine then passes through its cycle of operation as follows:—Starting at a discharge pressure lower than normal with the machine under the control of a constant volume governor, a flow of air larger than the average condition, due to the said conditions, is automatically caused to pass through the machine by the low pressure, and this large flow of air is acted upon properly by the discharge vanes in accordance with the general idea of their functioning, and a pressure is built up which becomes higher than the normal; but the fact of this high pressure having been generated automatically tends to decrease the flow of air, hence as soon as the flow of air is decreased to a certain critical point, the discharge vanes cease to perform their proper function and this causes the pressure to automatically drop to the point which was assumed at the beginning of the cycle. In other words, a wave of pressure has passed through the

machine and the conditions existing are the same as at the beginning of the wave. Under these conditions the reservoir above mentioned, or capacity, contains air at a pressure higher than that which the machine is capable of generating and, therefore, there must be a flow of air from the reservoir through the machine and out of the inlet. As soon as the pressure drops in said reservoir or capacity to a point below that which the machine is capable of generating, the flow of air is reestablished through the machine and this flow of air immediately becomes somewhat larger than the average amount flowing, and the cycle of operation before described again takes place.

The object of my invention is to provide a means for checking these abnormal occurrences and to this end I locate in the intake pipe of the compressor a check valve which will stop the back flow of air referred to and thereby decrease the range of pressure pulsations generated by the compressor. This valve also prevents the back flow of air from affecting the governing mechanism proper.

In carrying out the invention I employ a butterfly valve whose lower part is heavier than the upper so that the valve has a self closing tendency. The effective area of the lower part is made greater than that of the upper part so that under the influence of a current of air entering the compressor said valve will be automatically opened to admit said air and will assume an inclined position in the intake pipe corresponding with the volume of air passing. In case however any back blast occurs the valve will be shut both by its weight and the action of the back current of air upon its rear surface. In this manner the back blast is prevented from acting upon the constant volume governor located on the inlet side of said valve and all trouble from this source is obviated. The arrangement also prevents the effect of throttling of the inlet from having any effect on the indications of the governor, the latter always dealing with air under atmospheric pressure. In making and mounting the valve care should be exercised to see that it is given a sufficient unbalanced area, that the parts should not be too heavy and that the friction in the bearings should be decreased as much as possible. It sometimes happens that it is desirable to utilize this butterfly valve simply as a throttling device.

For this purpose a lever can be attached to the valve spindle and provided with a latch that coöperates with a notched quadrant to enable it to be locked in the desired position. The parts are so arranged that by means of a single bolt the valve and lever can be connected and disconnected.

In the accompanying drawings, Figure 1 is a side elevation of a portion of the intake 10 pipe of a centrifugal compressor provided with my improved check valve. Fig. 2 is a cross-section of said pipe showing the valve and its operating parts, and Fig. 3 is a section of the pipe and valve at right angles to 15 Fig. 2.

The casing 1 of the compressor has a flanged neck 2 adapted to be attached to the flanged end of the intake pipe 3 through which the air is admitted to the compressor. 20 Interposed between said neck and pipe is the valve casing 4 which has on opposite sides the tubular necks 5, 6 in which are received the bearings 7, 8 for the journals of the spindle 9. The valve 10 is mounted on said spindle, being a disk adapted to fit snugly against the walls of the casing 4 when said valve is closed. The axis of the spindle passes a little above the axis of the pipe 3 and casing 4 so that the valve is unbalanced, 25 the larger portion of its area being below the spindle. The current of air passing through the pipe acts more powerfully against this part of the valve and swings it more or less open, as shown in Fig. 3. To assist in producing this action, suitable means are provided upon the front face of said valve for pocketing a portion of the incoming air, such for instance as an angle iron 11 forming a rib against which the air acts to hasten the 30 opening of the valve at starting and to hold it open thereafter.

The neck 5 has a flange 12 to which is secured by bolts 13 a bracket 14. A sleeve 15 is formed on said bracket, which extends 45 into the neck 5 and affords a housing for the journal bearing 7, which can thus be made of considerable length. The bracket supports a dash-pot 16 whose movable element 17 is connected by a rod 18 with an arm 19 50 on a hub 20 which is secured to the spindle 9. The dash-pot may be of any desired construction, and is arranged to permit an easy opening of the valve, but to retard its closing movements, so that it will be prevented 55 from banging when shut by a sudden back blast. In case it is desired to use the valve as a manually actuated throttle, a lever 21 is employed that is held on the spindle by means of a nut 22 which forces a hub 23 60 of the lever against a shoulder 24 on the hub 20. The lever is also provided with an arm 32 that coöperates with an arm 33 carried by the hub 20 that is fast on the valve spindle 9. The arms 32 and 33 are united 65 by a bolt 34. When the bolt is secured in

place the valve can be moved by the lever but when removed the lever has no direct control. It can, however, with its arm 32, act as a stop to limit the opening of the valve 10; this does not interfere with the 70 automatic closing of the valve to prevent surging. The lever is provided with a latch 25 sliding in guides 26 and urged by a spring 27 against the periphery of a notched quadrant 28. The quadrant is fastened to the 75 bracket by means of bolts 29. By moving the lever, any range of opening for the valve may be obtained within the limits of the quadrant. In case it is desired to place the valve with its spindle in an upright position, 80 the weight of the valve will be sustained by a collar 30 on said spindle bearing upon thrust washers 31.

In operation, the compressor draws in air through the pipe 3 which acts against the 85 unbalanced valve to open it and hold it open while the air is passing. If a back blast occurs, it acts against the rear of the valve and closes it, thereby preventing any disturbance in the speed regulator and compressor. By clamping the lever 21 to the spindle of the valve by the bolt 34, it can be operated as a throttle to regulate the amount of air passing through the intake pipe. Under this condition there is no automatic action of the valve. In the intake 90 3 of the compressor is a float 35 forming a part of a constant volume governing mechanism. To the float is connected a rod 36 that extends upwardly through the intake 100 pipe and is connected to a lever 37 that actuates the throttle valve or other controlling device of the motor driving the compressor. To the lever is also connected a rod 38 attached to the movable member of a dash-pot 39. This constant volume governing mechanism is covered in my United States Patent 919,953, dated April 27, 1909.

In accordance with the provisions of the patent statutes, I have described the principle of operation of my invention, together with the apparatus which I now consider to represent the best embodiment thereof; but I desire to have it understood that the apparatus shown is only illustrative, and 115 that the invention can be carried out by other means.

What I claim as new and desire to secure by Letters Patent of the United States is,—

1. The combination of a centrifugal air 120 compressor having an intake, a constant volume governor located in the intake, and an automatic check valve located in the intake between the governor and the compressor and operating to prevent back blasts.

2. The combination of a centrifugal air 125 compressor and its intake, a constant volume governor located in the intake, and a valve located in the intake between the governor and the compressor which is unbal-

130

anced, is moved by the fluid passing through the pipe and has a tendency to close.

3. The combination of a centrifugal air compressor having an intake, a governing device for regulating the output of the compressor, and valve means located in the intake and operating to check back flow of the air.

4. The combination with the intake pipe of a centrifugal air compressor, of a governing device for the compressor arranged in the intake pipe, and a butterfly valve located in the pipe adjacent to the governing device and mounted upon a spindle, said valve having the area of its portion on one side of the axis of the spindle greater than that of its portion on the opposite side of said axis so that air flowing to the compressor tends to open the valve and air flowing back through the compressor tends to close the valve.

5. The combination with the intake pipe of a centrifugal air compressor, of a governing device located in the intake pipe, a butterfly valve arranged in the pipe adjacent to the governing device, said valve being adapted to open to the incoming air and to be moved toward its closed position by the back flow of the air, and a dash pot for retarding the closing movements of the valve.

6. The combination with the intake pipe of a centrifugal air compressor, of a governing device located in the intake pipe, a butterfly valve arranged in the pipe for checking back flow toward the governing device, said valve being adapted to be moved by the action of the flowing air when de-

sired, a lever adapted to be secured to the spindle of the valve, an abutment carried by the lever for limiting the opening of the valve by the air current, a latch on the lever, and a notched quadrant coöperating with the latch to hold the valve in a given relation to said device when desired.

7. The combination of a centrifugal air compressor and its intake, a constant volume governor located in the intake, a valve also located in the intake between the governor and the compressor, and a means located external to the intake for moving the valve.

8. The combination of a centrifugal air compressor and its intake, a constant volume governor located in the intake, a butterfly valve also located in the intake between the governor and the compressor, and a lever for moving the valve to decrease the effects of back blasts of air on the governor.

9. The combination of a centrifugal air compressor and its intake, a float located in the intake that rides on the incoming current of air and forms a part of a governing mechanism, and a valve that closes automatically to prevent back blasts of air from the compressor from forcing the float downward.

In witness whereof, I have hereunto set my hand this thirteenth day of November, 1911.

RICHARD H. RICE.
